UNITED STATES PATENT OFFICE.

HENRY A. DORTCH, OF DES MOINES, IOWA.

SPARK-PLUG.

1,216,092.

Specification of Letters Patent. Patented Feb. 13, 1917.

Application filed February 2, 1916. Serial No. 75,828.

To all whom it may concern:

Be it known that I, HENRY A. DORTCH, a citizen of the United States, residing at Des Moines, in the county of Polk and State of Iowa, have invented a new and useful Spark-Plug, of which the following is a specification.

The present invention appertains to spark plugs, and aims to provide a novel attachment for spark plugs to protect the electrodes from oil, so that the spark plug utilizing the attachment is not liable to foul.

It is the object of the invention to provide a protector attachable to the inner end of a spark plug to inclose the electrodes whereby the oil within the cylinder to which the plug is attached cannot be forced against the electrodes or insulated parts, and this will avoid the difficulties incident to ordinary spark plugs due to the presence of oil and resultant soot or carbon upon the electrodes.

It is also within the scope of the invention to provide a spark plug protector of the nature indicated which is extremely simple and inexpensive in construction, and which may be used upon various spark plugs, the device being practical and efficient in use.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

Figure 1 is a sectional view of a spark plug provided with one form of protector, portions being shown in elevation.

Fig. 2 is a cross section taken on the line 2-2 of Fig. 1.

Fig. 3 is a view similar to Fig. 1 illustrating a modified form of protector.

Fig. 4 is a cross section on the line 4-4 of Fig. 3.

The spark plug illustrated is of ordinary construction, embodying a metallic shell 1 having a reduced terminal 2 adapted to be threaded into the cylinder, and an insulator 3 is secured within the shell 1 as usual by

means of gland nut 4. A central conductor 55 rod or stem 5 is engaged through the insulator 3 and is provided at its inner end with the central electrode 6.

The protector 7 illustrated in Figs. 1 and 2 is of cup-shape, and has a reduced portion 8 surrounding its mouth and threaded into the inner or lower terminal 2 of the shell 1 to attach the protector to the shell so as to inclose the electrode 6, the protector 7 seating against the end of the shell. The 60 protector 7 has a chamber 9 into which the electrode 6 projects, and the bottom or closed end of the protector 9 is rounded or convexed, as at 10, to deflect the oil laterally away from the protector when the oil is 65 forced toward the plug during the compression stroke or otherwise.

The protector 7 has a peripheral or circumferential groove 11 adjacent its bottom or closed end, and the protector has diametrically opposite slots or apertures 12 extending from the chamber 9 to the groove 11. It will thus be observed that the protector 7 has a peripheral or annular rib between the groove 11 and rounded deflecting 70 end 10, so that the apertures 12 are more effectively protected from the oil. The apertures 12 permit the carbureted air to circulate through the protector around the electrodes, in order that the spark will 75 ignite the charge as usual.

In the present case, the grounded electrode is carried by the protector, and embodies a diametrical pin 13 providing the electrode within the chamber 9 beyond but 80 adjacent the end of the electrode 6, so that the sparks will jump the gap between the electrodes within the chamber 9.

When the protector 7 is used upon the plug, it protects the electrodes, so that the 85 oil and other extraneous matter cannot encounter the electrodes or insulated parts, and this prevents the plug from fouling, but does not impair the utility of the plug for purpose of ignition. The rounded or 90 converted end of the protector is of advantage since it deflects the oil laterally away from the electrodes, and it will also be observed that the protector incloses the electrodes and is imperforate with the exception of the restricted lateral apertures or 95 openings through which the carbureted air can circulate.

The plug illustrated in Fig. 3 is of the same construction as the plug above described, but the grounded electrode 6' is attached to the terminal 2 of the shell 1 in the ordinary manner to coöperate with the central electrode 6. The protector 7' in this case is stamped from suitable sheet metal and is of rounded or convexed formation to protect the electrodes, the rim of the protector 7' having diametrically opposite arcuate lips 8' parallel with the axis of the protector and soldered or otherwise secured to the terminal 2 of the shell 1. The lips 8' provide lateral openings 12' disposed opposite one another. The protector 7' prevents the oil from being forced against the electrodes and deflects the oil laterally away from the electrodes.

The protectors can either be made integral with or detachable from the shells, and the details thereof can be varied within the scope of what is hereinafter claimed in adapting the invention to various plugs and conditions.

Having thus described the invention, 25 what is claimed as new is:

A cup-shaped spark plug protector whose mouth portion is reduced for engaging within one end of the shell of a spark plug, said protector being adapted to inclose the 30 central electrode of the spark plug and having a closed bottom, the walls of the protector having two diametrically opposite openings adjacent the bottom thereof, and a diametrical pin carried by the walls of 35 the protector adjacent the bottom thereof below and at right angles with the axis of said openings and providing an electrode coöperable with the central electrode of the spark plug. 40

In testimony that I claim the foregoing as my own, I have hereto affixed my signature in the presence of two witnesses.

HENRY A. DORTCH.
